UNITED STATES PATENT OFFICE.

GEORGE W. MACKENZIE, JR., OF BEAVER, AND RAYMOND CROWDER, OF EDGEWOOD, PENNSYLVANIA, ASSIGNORS TO GUARANTEE LIQUID MEASURE COMPANY, OF ROCHESTER, PENNSYLVANIA, A CORPORATION OF DELAWARE.

DESIGN FOR A LIQUID-DISPENSING-PUMP CASING.

51,986.

Specification for Design.

Patented Apr. 23, 1918.

Application filed November 12, 1917. Serial No. 201,640. Term of patent 14 years.

To all whom it may concern:

Be it known that we, GEORGE W. MACKENZIE, Jr., and RAYMOND CROWDER, citizens of the United States, residing at Beaver, in the county of Beaver and State of Pennsylvania, and Edgewood, in the county of Allegheny and State of Pennsylvania, respectively, have invented a new, original, and ornamental Design for Liquid-Dispensing-Pump Casings, of which the following is a specification, reference being had to the accompanying drawing, forming a part thereof.

Figure 1 is a front plan view of a pump embodying our design; and

Copies of this patent may be obtained for five cents each, by addressing the "Commissioner of Patents, Washington, D. C."

Fig. 2 is a side view of the same.

The pump consists of a base portion A and cylindrical tank portion B surrounded by a metallic casing C, the cylindrical tank portion B being mounted between top and bottom members D and E.

We claim:—

The ornamental design for a liquid dispensing pump casing, as shown and described.

In testimony whereof, we hereunto affix our signatures.

GEORGE W. MACKENZIE, JR.
RAYMOND CROWDER.
